CEILING

Ladislaus Navratil, Budapest, Hungary

Application December 24, 1930, Serial No.
504,554, and in Hungary December 31, 1929

4 Claims. (Cl. 72—66)

Ferro-concrete ceilings are known which comprise essentially parallel ferro-concrete carriers forming beams supported by the main walls of the building, with hollow bodies built in between the carriers, these bodies filling in the spaces between the carriers and being also adapted to form the finished face of the ceiling and the frame therefor, so that the conventional wooden backing may be dispensed with.

With ceilings of this type the hollow filling bodies are generally of the shape of railway rails having a head and a broad flat-base, presenting longitudinal channels and made of baked clay, and in constructing the ceiling they are laid in rows, at right angles to the main walls, on a flat horizontal wooden frame with the edges of the base flanges touching; thus the open topped channels are formed between the several rows, these channels forming moulds for the ferro-concrete carriers and the ceiling. The carriers are produced by filling concrete into the channels and tamping it down in conventional manner after placing the iron reinforcement in position, these carriers thus presenting at their lower ends longitudinal ribs engaging the sides of the hollow bodies. The latter are thus suspended by their heads from the ribs of the carriers, while the flanges at the base of the hollow bodies extend laterally underneath the carriers up to their central longitudinal planes, thus completely covering the undersides of the carriers.

This form of ceiling is satisfactory as far as it offers a smooth, flat face free of cracks and flaws, and it is an improvement on other forms of ferro-concrete ceilings as regards sound and heat insulating properties, and it is shallow, but it has the disadvantage that it involves comparatively very small distances between the carriers, by reason of the hollow bodies being of very limited width, so that these ceilings require the use of too many carriers which not only make the ceiling very difficult to construct but also increase its weight and cost of production to an appreciable extent. The reason for this is that the technical difficulties of construction prevent the hollow bodies being made wider than 30 centimeters, which, having regard to the fact that the flanged bases must reach up to the central longitudinal planes of the carriers, reduces the distance between the carriers to 30 centimeters in the finished ceiling.

The object of the present invention is to provide a ferro-concrete hollow ceiling of this kind with hollow bodies and carriers therefor in which not only is the above mentioned serious

disadvantage obviated, but it also enables the distance between the carriers to be doubled at least, but the particular construction of the carriers and hollow bodies increases the static safety and strength of the ceiling. This also results in 60 the weight as well as the cost of production of the ceiling being considerably reduced, without affecting the above mentioned advantages of such a ceiling.

In the construction of ceiling according to the invention at least two hollow bodies are arranged side by side between each two adjacent ferro-concrete carriers, at right angles to the run of the latter and filling the spaces between said carriers. These hollow bodies are preferably arranged with 70

their longitudinal axes in parallel to the carriers, and they rest in a vault like manner with their outer longitudinal sides against the abutment-like inclined faces of the carriers. This inclination of the side faces of the carriers, together with 75 the correspondingly inclined formation of the adjoining side faces of the hollow bodies, is an important feature, for the reason that the resultant pressure of the hollow bodies subjects the carriers to a favourable strain, namely compression, whereas in the case of known ceilings of this type, where only one hollow body occupies the space between each pair of carriers, the hollow bodies are only suspended at their heads from the rib-like enlargement of the lower ends of the 80 carriers, so that the latter are subjected to an unfavourable stress, namely tension, in the direction of their height. These hollow bodies according to the invention are in the form of left and right hand side separately unsymmetrical 85

bodies, but collectively provide a single symmetrical body which forms a self-supporting flat hollow dome filling the space between two carriers. In order to increase the strength of such a hollow structure, the two hollow bodies may be 90 rigidly united at the adjoining faces as by mortar cement, or interlocking by longitudinally disposed tongue and grooves formed on the adjoining faces, or by rabbeting, overlapping or serrating the ad- 95

joining faces and so forth. If a greater distance between the carriers is desired, more than two adjacent hollow bodies may be arranged between two adjacent carriers. In this case such a self- 100 supporting ceiling formed of the hollow bodies may be strengthened by those sides of the hollow bodies remote from the carriers being inclined, and the other hollow bodies to be inserted between these two hollow bodies being wedge shaped so that they 105 engage in the manner of key stones of an arch.

110

between the two outer hollow bodies and thus support the latter and each other mutually.

Another method of fixing the ferro-concrete hollow ceiling may be effected according to the 5 invention by providing open topped spaces between adjacent hollow bodies of the ceiling and filling such spaces with cement or the like, the latter when hard forming wedges which act in the manner of arch key stones.

10 Further, the strength of the ceiling may be increased by a special construction of the ferro-concrete carriers, heretofore rendered impossible owing to the small distance between the carriers, this construction consisting in providing the 15 ferro-concrete carriers with a broad foot plate between their points of inflection and supports, said foot plates providing the carriers in these sections with a statically correct I shaped section to accord with the negative moments acting at 20 this part. The hollow bodies adjacent the carriers are of course, correspondingly shaped to suit this I shaped profile of the carriers in these sections.

Obviously in such cases where there is no objection to the free use of cement, the ferro concrete carriers may be also provided for the whole of their length with such a plate on their lower extremities that is to say they may be of I section.

Several constructional forms of ferro-concrete 30 ceilings according to the invention and their hollow bodies are shown in section longitudinally of the carriers and hollow bodies, and wherein.

Figs. 1, 6, 8, 9 and 10 show different constructions of ceilings with only two adjoining hollow 35 bodies.

Figs. 7, 15 and 16 are similar views of ceilings having three adjoining hollow bodies.

Figs. 10 and 16 show the particular construction of the ceiling between the points of inflection and the places where their carriers are 40 inserted.

Figs. 2 to 5 and Figs. 11, 12 and 14 show different constructions of hollow bodies for the ceiling, the latter three figures being shown to a 45 larger scale.

Fig. 13 shows a cover plate for the lower carrier side for use with the form of ceiling shown in Figs. 10 and 16, and

Fig. 17 shows diagrammatically in vertical longitudinal section one end of a carrier of the ceiling.

Referring to the drawings, 1 designates the ferro-concrete carriers of the ceiling, and 2a 2b are the hollow bodies adjoining said carriers, 55 whilst in Figs. 10, 12 and 16 the hollow bodies are designated 2A and 2B. 2c designates a third hollow body which may be introduced between these hollow bodies. The hollow bodies which are advantageously made of clay in the 60 form of prismatic hollow bricks, open at opposite ends, have in all cases a flat base, whilst the top wall may be of any desired shape, and the sides are inclined, the inclination varying according to the particular arrangement and position of the hollow body. In the case of the 65 hollow bodies 2a, 2b or 2A, 2B adjoining the carriers 1, the longitudinal sides adjacent the carriers are always at an obtuse angle to the base, and their opposite longitudinal sides are at right 70 angles or at an angle less than a right angle to the base; the base extends laterally outwards to form a flange 3 on that side adjacent the carriers, the width of this flange being equal to half the width of the base of the ferro-concrete 75 carrier 1. The overall width of the base of a

hollow body including the flange is approximately equal to 30 centimeters, which accords with the dimensions of the known separate hollow bodies, so that a pair of hollow bodies 2a and 2b arranged as shown with their flangeless sides, adjoining forming together a single symmetrical hollow body of twice the width of conventional hollow bodies, with as a result double the usual distance between the carriers. The two hollow bodies may be connected to form a unitary body 80 by an interlock between their adjoining sides produced as by a tongue and groove joint, as shown in Figs. 1 and 2, or by a stepped engagement according to Figs. 3 and 4, or by a serrated joint 85 as shown in Fig. 5 or other connection. The adjoining sides may also be smooth (Figs. 6 and 8), in which case they may be connected by a binding medium such as cement mortar. Obviously hollow bodies connected by interengaging 90 means may also be cemented together at the joint. The top side of the hollow bodies may be flat or otherwise shaped, as for instance, roof shaped, as shown in Fig. 4, or waved according to Fig. 5 and so forth. These bodies may be devoid of division walls as shown in Fig. 3, or 100 divisions 4 may be provided as shown in the other figures, and there may be one or more of such divisions. The shape of the carriers is determined by the trapezium shaped channels between the successive adjoining pairs of hollow 105 bodies 2a and 2b, or 2A and 2B, presenting the inclined side, and such carriers are accordingly of trapezium shape in cross section, that is to say their sides diverge downwards. These inclined sides of the carriers 1 form the abutment 110 against which bear the vault constituted by the hollow members 2a and 2b or 2A and 2B or 2c which fill the space between adjoining carriers. (Figs. 1, 6, 7, 8, 9 and 15.) These carriers 1 are provided at the bottom with the conventional 115 iron reinforcement wires 5, and at the top they present the top plates 1a which take the compression stresses. Obviously these plates 1a, as shown in Figs. 9, 10, 15 and 16 may be united to form a single continuous plate without departing from the spirit of the invention. On top of the plates 1a is the usual slag or other filling 6, Fig. 1, on which are placed the beams 8 carrying the flooring boards 7.

Figs. 7, 15 and 16 show constructions which are 120 particularly adapted for ceilings having narrow spans and comparatively small loads, and wherein the distance between the carriers is increased to 75 to 30 centimeters by means of a third hollow body 2c introduced between the pairs of 125 hollow bodies 2a and 2b or 2A and 2B. In this case the flangeless side faces of the two hollow bodies 2a and 2b or 2A and 2B are again inclined and diverge upwards, whilst the third hollow body 2c placed between them is wedge shaped, so that 130 it acts in the manner of a key stone between the two other hollow bodies 2a and 2b or 2A and 2B. This third body 2c may be lower than the two others, or it may be of the same height as indicated by broken lines in Figs. 7, 15 and 16. 140 Further, in lieu of this third hollow body 2c there may be one or more solid bricks.

In all constructional forms of such a ceiling comprising hollow bodies the bases of all of them lie in a common plane, so that the underside of 145 the ceiling is not only completely flat but after the bases of the members 1 have been covered by the flanges 3 of the hollow bodies, or as shown in Figs. 10 and 16, by a cover plate 11 of the same material, the ceiling is composed throughout of 150

the same material, i. e. brick, so that the coat of plaster on the underside cannot possibly develop flaws or cracks as a result of temperature fluctuations.

5 For the sake of completeness there is shown in Fig. 8 a construction of ceiling which may be considered of secondary importance in view of its greater weight and cost of production, and wherein the hollow bodies 2a and 2b and the carriers are made of concrete. In this case flanges 3 of the hollow bodies of clay for covering the ferro-concrete carriers are dispensed with, and in lieu thereof there are provided boards 9 for closing the channels between the 10 several rows of hollow bodies, and the hollow bodies have to be laid with the aid of templets or by measuring.

Figs. 9 and 10 and 15 and 16 show constructions of ceilings in which there are spaces 10 between the adjacent hollow bodies, these spaces being closed at the bottom and open at the top, and which are filled in with concrete or mortar during the building of the ceiling, this filling when hard, forming keys disposed between the 15 hollow bodies and acting in the manner of key stones in an arc. These spaces 10 may be produced either by providing the opposite longitudinal sides of adjacent hollow bodies 2a, 2b or 2A, 2B with inclinations directed in opposite directions, (Figs. 9 to 12), or the lower edge of one or both of complementary longitudinal sides of the hollow bodies are provided with a narrow longitudinal rib 3a which separates the hollow bodies, as shown applied to the centre body 2c in Figs. 14 to 16. In both cases the adjoining bodies are thus only able to touch along the lower longitudinal edges (Figs. 9-12 and Figs. 15 and 16), a space 10 being left at the 20 top which, in the first case, tapers outwards towards the top, (Figs. 9-12), and in the second case the space is of equal width from top to bottom and is determined by the width of the lower rib or ribs 3a.

Figs. 10, 12, 16 and 17 relate to constructions 45 of ceilings in which the fastening of the hollow bodies is effected by the particular construction of their carriers, that is to say, by the hollow bodies adjoining the carriers in the sections to the right of $x-x$ between the points of inflection and the supports for the carriers (Fig. 17).

In these sections, where only negative moments occur, so that the lower parts of the carriers are subjected to compression strains and the upper to tensile strains, the lower part 55 of the carriers are so dimensioned as to accord with the compression strains occurring at this part, the foot plate 1b being broadened so that the carriers are of substantially I section in these sections (Figs. 10 and 16).

60 Obviously the reinforcement wire 5 is displaced from the point of inflection to the upper carrier part in accordance with the tensile strains occurring in the upper part of the carrier, as shown to the right of $x-x$, Fig. 9.

65 The hollow bodies 2A and 2B adjoining the carriers in this section are so formed in accordance with this I section that the lower part of the longitudinal sides adjoining the carriers, together with the lower flange 3 engaging under 70 the carrier, is set back to the extent of approxi-

mately half the width of the hollow body (Fig. 12), so that a recess A is formed on these sides of the bodies in which the foot plate 1b of the carrier engages.

Between the points of inflection of the carriers (to the left of $x-x$ in Fig. 17) where there are only negative moments, the carriers may be constructed in the manner previously described, where they are provided in any case with suitable head plates 1a to take the compression strains occurring in the upper part of the carrier, these head plates giving the carriers an I section, while the tensile strains occurring in the lower part of the carrier are taken by the iron reinforcements 5 arranged at this part.

Where the quantity of cement used is of no consequence, the carriers may be of I section throughout their length along the lower belt, in order to simplify the production of the ceiling.

With this I shaped section of the lower part 95 of the carriers the set back flanges 3 of the hollow bodies 2A and 2B do not completely engage under the now broadened base of the carrier 1, a space is left between pairs of flanges 3 which is filled in with a plate 11 (Fig. 13) so that the uniformity of the material brick forming the face of the ceiling is preserved, this plate also serving as a lower cover for the production of the carrier 1. This plate 11 is supported by the inclined ends of the flanges 100 3 of the hollow bodies 2A and 2B as shown in Figs. 10 and 16.

It may be finally remarked that in order to ensure the concrete or plaster adhering firmly to the hollow bodies 2a, 2b, and 2A, 2B, as well 110 as to the cover plates 11, the hollow bodies and plates are preferably provided on their appropriate faces with straight or dove-tailed longitudinal grooves 12, as shown in Figs. 11 to 14.

What I claim is:

1. A ceiling construction, comprising ferro-concrete carriers, and a plurality of hollow bodies interposed between adjacent carriers in series at right angles to their longitudinal run, the lower portions of said carriers being of I section.

2. A ceiling construction, comprising ferro-concrete carriers, and a plurality of hollow bodies interposed between adjacent carriers in series at right angles to their longitudinal run, the lower portions of said carriers being of I section between 120 their points of inflection and their supports.

3. A ceiling construction, comprising ferro-concrete carriers, and a plurality of hollow bodies interposed between adjacent carriers in series at right angles to their longitudinal run, the lower portions of said carriers being of I section, the longitudinal sidewalls of the bodies adjoining the carriers being set back at their lower portions to correspond with the lower portions of the 130 carriers.

4. A ceiling construction, comprising ferro-concrete carriers, and a plurality of hollow bodies interposed between adjacent carriers in series at right angles to their longitudinal run, the bases 140 of the hollow bodies being extended laterally beyond the sides adjacent to the carriers thereby to form a flange in engagement with the underside of the carriers.

LADISLAUS NAVRATIL. 145
